UNITED STATES PATENT OFFICE

2,663,774

ELECTROMAGNETIC TRIP CIRCUIT BREAKER

John B. MacNeill and Harry J. Lingal, Pittsburgh, Pa., assignors to Westinghouse Electric Corporation, East Pittsburgh, Pa., a corporation of Pennsylvania

Application July 22, 1950, Serial No. 175,373

19 Claims. (Cl. 200—108)

1 This invention relates to circuit breakers and more particularly to circuit breakers of the type used for controlling light to moderate power distribution circuits.

An object of the invention is to provide a circuit breaker embodying a novel trip device that is operable to trip the breaker after a relatively long time delay in response to overload currents of relatively low value, after a relatively short time delay in response to overload currents of intermediate value below a predetermined value and instantaneously in response to overload currents above said predetermined value or short circuits.

Another object of the invention is to provide a circuit breaker having a trip device embodying a time-delay device of the fluid dashpot type in which time delays of different duration are effected in the operation of the trip device in different ranges of overload currents by admitting fluid to the dashpot at different rates.

Another object of the invention is to provide a circuit breaker having an electroresponsive trip device embodying a novel time-delay device of the fluid dashpot type in which time delays of different durations are effected in the operation of the trip device by the operation of a single valve means to admit fluid to the dashpot at different rates.

A further object of the invention is to provide a circuit breaker having an electroresponsive trip device embodying a novel time-delay device of the fluid dashpot type in which time delays of different durations are effected in the operation of the trip device by the operation of a single valve means to admit fluid to the dashpot at different rates, the valve means being selectively operated electromagnetically in response to overload currents of different magnitudes.

Another object of the invention is to provide a circuit breaker with an electroresponsive trip device embodying a novel time-delay means of the fluid dashpot type in which time delays of different durations are effected in the operation of the trip device by the operation of a single valve means to admit fluid to the dashpot at different rates, the valve means being operative by a plurality of armatures selectively responsive to overload currents of different magnitudes.

The novel features that are considered characteristic of the invention are set forth in the appended claims. The invention itself, however, both as to structure and operation, together with additional objects and advantages thereof, will be best understood from the following detailed

2 description of a preferred embodiment thereof, when read in connection with the accompanying drawings.

In said drawings:

5 Figure 1 is an elevational view, partly in section, of a circuit breaker embodying the principles of the invention;

Fig. 2 is an enlarged sectional view taken substantially along line II—II of Fig. 4 and showing the adjusting means for one of the time-delay valve-operating armatures;

Fig. 3 is a vertical sectional view through the trip device taken substantially along line III—III of Fig. 4 and looking in the direction indicated by the arrows;

Fig. 4 is a sectional plan view of the time-delay device taken substantially along line IV—IV of Fig. 3 and looking in the direction indicated by the arrows;

Fig. 5 is an elevational sectional view taken substantially along line V—V of Fig. 4, looking in the direction of the arrows and showing the adjusting means for the short-time-delay armature;

Fig. 6 is an elevational sectional view taken substantially on line VI—VI of Fig. 4, looking in the direction of the arrows and showing the control valve for the time-delay device together with the adjusting means therefor;

Fig. 7 is an elevational view of the time-delay device showing the scale plate and the several adjusting knobs;

Fig. 8 is a schematic view of the trip device illustrating the several adjusting means for the time-delay device; and

Fig. 9 is a schematic diagram showing the range of adjustment of the trip device.

Referring to Fig. 1 of the drawings, the circuit breaker includes a plurality of pole units each comprising a contact structure indicated generally at 11 and an overcurrent trip device indicated generally at 13. The contact structure and the trip device for each pole unit are mounted on a separate insulating base 15 which is rigidly secured to a metal supporting panel 17. Since the pole units are alike, only the center pole unit is illustrated and described herein.

The contact structure 11 comprises stationary main and arcng contacts 19 and 21 both secured on the inner end of a terminal conducting bar 23 and cooperating movable main and arcng contacts 25 and 27. The movable contacts are rigidly secured to a contact-carrying member 29 pivotally mounted by means of a pivot pin 31 on a U-shaped switch arm 33 which, in turn, is piv-

totally supported by pivot means 35 on brackets 37 rigidly mounted on the insulating base 15.

The movable contact-carrying member 29 is electrically connected by means of a flexible conductor 39 to the energizing coil of the trip device 13. A spring 41 compressed between the movable contact-carrying member 29 below its pivot 31 and the insulating base 15 provides contact pressure in the closed position of the breaker and also biases the movable contact structure in 10 opening direction.

The movable contact structure is normally maintained in the closed position by means of an operating mechanism indicated generally at 43 mounted in a U-shaped frame 45. The frame 15 45 is supported on a platform 47 which forms a cross member of a generally U-shaped main bracket comprising a pair of spaced side members 49 rigidly connected at their outer ends by the cross member or platform 47. The platform 47 20 extends substantially across the width of the breaker and the side members 49 are suitably secured to the metal panel 17 on the outside of the two outer pole units of the breaker.

The operating mechanism includes a lever 51 25 mounted on a pivot pin 53 supported in the side members of the frame 45. The lever 51 carries a rod 55 extending across all of the poles of the breaker and is connected by means of insulating connecting members 57 to the pivot pins 31 in 30 the free ends of the switch arms 33 for the several poles of the breaker so that upon operation of the rod 55 the movable contacts of all of the poles move in unison.

An operating linkage comprising toggle links 59, 61 and 63 is provided to releasably hold the lever 51 and consequently the movable contacts in the closed position and to operate the movable contacts to open and closed positions. The toggle link 59 is pivotally connected to the lever 51 by means of a pivot pin 65 and the toggle link 63 is pivoted on a fixed pivot 67 supported in the frame 45. The toggle link 61 is pivotally connected to the links 59 and 63, respectively, by knee pivot pins 69 and 71.

The linkage 59, 61, 63 comprises two toggles, one of which 59-61 may be designated as the tripping toggle and the other 61-63 as the closing toggle. The tripping toggle 59-61 is normally slightly underset above a line drawn through the centers of the pivot pins 65-71, and the closing toggle 61-63 is normally underset below a line drawn through the centers of pivot pins 67-69. The closing toggle 61-63 is normally prevented from collapsing downward by a support member 73 pivoted on a pivot pin 75 supported in the frame 45 and having a shouldered portion engaging under the knee pivot pin 71.

The tripping toggle 59-61 is normally biased in a direction to cause its collapse by a component of the force of the springs 41 which bias the movable contact structures for the three poles of the breaker in opening direction and bias the connecting member 57 toward the left (Fig. 1). The tripping toggle 59-61 is normally prevented from collapsing by means of a main latch member 77 pivoted on the pin 53 and connected by means of a link 79 to the knee pin 69 of the tripping toggle.

The main latch member 77 is held in latching position by an intermediate latch lever 81 pivoted on the pin 75. The intermediate latch lever 81 carries at its upper end a latch roller 83 engaging the main latch 77 and at its lower end has a latching portion 85 normally engaging a latch

member 87 on a channel-shaped latch 89 pivoted on a pivot pin 91 in the frame 45. A spring 93 serves to bias the latch lever 81 and the latch 89 to their latching positions.

A trip bar 95, extending across all of the poles of the breaker, is rigidly mounted on the right-hand end of the channel-shaped latch 89 and has insulating brackets 97 (only one being shown) secured thereto, there being a bracket 97 for each pole of the breaker. Each of the brackets 97 has a headed screw 99 adjustably mounted thereon for cooperating with the trip device 13 of its associated pole in a manner to be presently described.

The breaker is tripped open manually by means of a cam member 101 mounted on the inner end of a handle shaft 103 journaled in a bearing 105 mounted in the front piece of the frame 45. The handle is not shown in the drawings but is rigidly secured to the outer end of the shaft 103 and biased in both directions to a central position in a well-known manner by means of a spring 107.

Rotation of the handle shaft 103 in tripping direction causes the cam member 101 to engage and actuate the latch member 89 in counterclockwise or unlatching direction to unlatch the intermediate latch lever 81, which, in turn, releases the main latch 77. This permits the tripping toggle 59-61 to collapse upwardly to effect opening of the breaker contacts. During the collapse of the tripping toggle, a portion 109 of the toggle link 61 engages and actuates the support member 73 to a non-supporting position, thereby freeing the closing toggle 61-63. The closing toggle thereupon collapses downwardly and during its collapse resets and relatches the tripping toggle 59-61.

The breaker contacts may now be operated to the closed position by rotating the shaft 103 and the cam 101 in the direction opposite to the tripping direction. This causes the cam 101 to engage a projection 111 on the closing toggle link 63 and moves this link counterclockwise about its pivot 67 until the support member 73 resumes its supporting position below the knee pivot pin 71. During the closing operation, the link 79 prevents collapse of the tripping toggle 59-61 which acts as a thrust transmitting means and moves the movable contact structure to the closed position.

The breaker is automatically tripped open by operation of the trip device 13 for any pole of the breaker. The trip device includes generally a tripping electromagnet 113 (Figs. 1 and 3) and a time-delay device 115. The tripping magnet 113 includes a C-shaped magnet yoke 117. The ends 123 of the magnet yoke form mounting feet and are drilled and tapped to receive mounting bolts 125 and 127 as shown in Fig. 1.

The upper end of a stationary magnet core 129 (Fig. 3) is provided with an internal thread which cooperates with a threaded nipple 137 disposed in an opening in the magnet yoke to rigidly secure the stationary core 129 to the magnet yoke.

Surrounding the stationary core member 129 is an insulating tube 139 around which is disposed the energizing coil 141 of the magnet.

As shown in Fig. 1, the bolt 125 which secures the upper end of the magnet yoke to the base 15 also secures the flexible conductor 39 to the upper turn of the coil 141. The lower turn of the coil 141 is formed into a lug 143 which, together with the inner end 145 of a terminal 147, is secured to the base 15 by means of a bolt 149. A tubular member 151 (Fig. 3) of magnetic material is mounted in an opening in the lower portion of

the magnetic yoke 117 and extends upwardly within the insulating tube 139. Disposed within the tubular member 151 is a movable core member or armature indicated generally at 153 comprising an upper portion 155 and a tubular lower portion 157. The armature 153 is provided with a central opening through which extends a trip rod 161 extending axially through the movable armature 153, an opening in the stationary core member 129 and an opening in the nipple 137. A spring 163 coiled about the trip rod 161 is compressed between a counterbore in the armature 153 and a collar 159 which bears against a spring clip 165 seated in an annular groove in the trip rod 161.

The trip rod 161 is moved upwardly to trip the breaker under the control of the time-delay device 115 which comprises, generally, a movable abutment or flexible diaphragm 167 (Fig. 3) cooperating with the lower end of the trip rod and a valve element for admitting air to the space below the movable abutment or diaphragm at various rates to provide different amounts of time delay. The flexible diaphragm is disposed in a chamber formed in an upper housing member 171 and a lower housing member 173, both of said housing members being formed of molded insulating material. The outer edge of the diaphragm 167, together with a sealing gasket 175, is clamped between the housing members to form an airtight seal. The housing members 171-173 are secured together and rigidly secured to the magnet yoke 117 by means of bolts (not shown). The central portion of the diaphragm 167 is clamped between upper and lower clamp members 179 and 181, respectively, the upper clamp 179 having an annular projection 183 extending downwardly through an opening in the lower clamp 181 and formed over against the lower face of the latter to form an airtight seal.

Secured to the lower end of the trip rod 161 is a sleeve 185 provided with a flange 186 to the upper face of which is suitably attached a facing 188 of a tough resilient material. The sleeve 185 is disposed in a central opening 190 in the upper clamp member 179. An annular valve seat 192 formed on the clamp member 179 about the opening 190 is provided to cooperate with the facing 188 to close the opening 190 upon upward or tripping movement of the trip rod 161. The lower portion 157 of the movable armature extends downwardly through an opening in the upper wall of the housing member 171 and is normally seated on the upper face of the upper clamp member 179 surrounding the opening 190.

Disposed in the space above the diaphragm 167 is a ring 195 having an inwardly extending flange 197. Disposed between the flange 197 and the upper wall 199 of the housing member 171 is a filter 201 for filtering any air that may be drawn into the chamber through an opening 203 (Fig. 6) formed in the wall 199 of the housing. Ordinarily in the operation of the time-delay device, air is merely transferred from the space above the diaphragm to the space below the diaphragm. However, due to variations in temperature of the surrounding atmosphere, the device may "breathe" air onto and out of the chamber. The filter 201 is provided to prevent foreign matter from being drawn into the chamber by such "breathing."

Since the spaces above and below the diaphragm 167 are sealed off from each other and the space above the diaphragm is at atmospheric

pressure, any force tending to raise the trip rod 161 will be restrained by the partial vacuum below the diaphragm. In order to control the rate of tripping movement of the trip rod 161, a single valve device indicated generally at 205 (Fig. 6) is provided to admit air to the space below the diaphragm 167 at varying rates to provide long time delay and short time delay in the tripping movement of the trip rod and also substantially instantaneous tripping movement of the trip rod 161.

The valve device 205 (Fig. 6) includes a valve member 207 having a tapered valve 209 at the lower end thereof cooperating with a tapered valve seat 211 formed in the housing member 171. The valve member 207 is disposed for sliding movement in a metal thimble 213 inserted in an opening 215 in the housing member 171 and having an enlarged portion 217 threadedly engaging the housing member. A spring 219 compressed between the valve 209 and the bottom of the thimble 213 biases the valve in closing direction. A passage 221 in the housing member 171 communicates the space above the diaphragm 167 to the opening 215 above the valve 209, and a passage 223 communicates the space below the diaphragm to the space below the valve 209. Thus, the valve 209-211 controls the passages 221-223 which communicate the spaces above and below the diaphragm 167. Openings 225 (only one being shown) are provided in the ring 195 to permit flow of air from the space inside the ring to the passage 221, the cross-sectional area of the openings 225 being at least equal to the cross-sectional area of the passages 221-223 at the narrowest point.

On long-time-delay tripping operations, in response to low overload currents, the valve member 207 is not moved but is normally maintained in slightly opened position by an adjusting device (to be described later) to admit air below the diaphragm for controlling the rate of tripping movement of the trip rod 161 on such operation. Upon the occurrence of an overload current in the higher range of overload currents below a predetermined value, the valve 207 is opened a predetermined amount by means of a secondary or short-time-delay armature 227 (Figs. 4 and 5). On overload current above the predetermined value or on short circuit currents an instantaneous armature 229 (Figs. 4 and 6) is actuated to move the valve 207 to its full open position to permit substantially instantaneous tripping movement of the trip rod 161.

The short-time-delay armature 227 is pivotally supported at its right-hand end (Figs. 4 and 5) by means of projections 231 which fit in openings in the right-hand wall of the housing member 171. The instantaneous armature 229 is similarly supported by projection 233 thereon. The armature 229 (Figs. 2 and 4) is biased to unattracted position by means of a spring 235 having one end attached to the armature and the other end attached to an adjustable member 237 threadedly engaging an adjusting screw 239. The member 237 is provided with a narrow pointer 241 which projects through a vertical slot 243 in a scale plate 245 (see also Fig. 7). The adjusting screw 239 is suitably secured to an adjusting knob 247 (Figs. 2 and 7) journaled in an opening in the housing member 173. Rotation of the knob 247 and the screw 239 moves the member 237 up or down, depending on the direction of rotation of the knob, and varies the tension of

the spring 235. This varies the pick-up point, that is, the minimum value of the overload current required to operate the armature 229.

A similar adjustment is provided for the short-time-delay armature 227 (Figs. 4 and 5). A 5 spring 249, one end of which is attached to the armature 227, has its other end attached to an adjustable member 251 (Fig. 4) similar to the member 237. The member 251 threadedly engages an adjusting screw 253 journaled in an 10 opening in the housing member 173 and is provided with a knob 255 (Fig. 7) for rotating the screw. The member 251 is also provided with a pointer 257 which projects through a vertical slot 259 in the scale plate 245. Rotation of the 15 screw 253 will move the member 251 up or down, depending on the direction of rotation, to vary the minimum overload current required to actuate the short-time-delay armature 227.

An opening 261 (Fig. 3) in the magnet yoke 117 provides an air gap for the magnetic circuit through the armature 229, and a similar opening (not shown) provides an air gap for the magnetic circuit through the armature 227. As shown in Fig. 4, each of the armatures 227 and 229 is provided with a recess 263, and each armature is adapted to engage under a head 265 on the upper end of the valve member 207 upon actuation of the armatures to effect opening movement of the valve member 207 and opening of the valve 209—211 (Fig. 6). This opens the previously described communication 221—223 (Fig. 6) and permits air to pass from the space above the diaphragm 167 to the space below the diaphragm to control the tripping movement of the trip rod 161. The rate of flow of air to the space below the diaphragm and consequently the rate of tripping movement of the trip rod is controlled by the amount of opening of the valve 209—211.

The extent of opening movement of the valve member 207 is adjustably controlled by means of an S-shaped stop member 267 (Figs. 4 and 5) to thereby determine the amount of time delay provided on short-time-delay tripping operations. The upper portion 269 of the S-shaped member 267 comprises an adjustable stop and is disposed in the path of valve-opening movement of the upturned end of the armature 227 to be engaged thereby and thus limit upward movement of the armature and limit the extent of opening of the valve 207. The center cross member 271 of the S-shaped member 267 has a threaded opening therein which is engaged by an adjusting screw 273, so that upon rotation of the screw 273 the S-shaped member 267 will be moved up or down, depending on the direction of rotation, to provide for greater or lesser opening movement of the armature 227 and, hence, greater or lesser opening movement of the valve 207.

The lower end of the adjusting screw 273 is rigidly fixed to a shaft 275 rotatable in an opening in the lower housing member 173, and the shaft is provided with an integral knob 277.

In order to give a visual indication of the setting of the adjustable stop 269 and, hence, of the short-time-delay setting, there is provided a pointer 279 (Fig. 5). The pointer is U-shaped and the two legs (only one being shown) thereof straddle the adjusting screw 273 and engage in notches 281 (only one being shown) on opposite sides of the adjustable stop member 267. The pointer 279 is biased downwardly by means of a spring 283 and has a reduced portion 285 extending through a slot 287 in the scale plate 245 to indicate the setting of the adjustable stop 269

and, therefore, the amount of time delay provided for the short-time-delay operation.

The valve 207 is adjustable to determine the amount of long time delay provided in the operation of the trip device by means of an adjustable S-shaped stop member 289 (Fig. 6). The stop member 289 is provided with a horizontally disposed stop 291 which is bifurcated to embrace the valve member 207. A collar 293 on the valve member 207 rests on top of the member 291 to determine the amount of opening of the valve 209—211 and, therefore, the amount of long time delay. A cross member 295 on the stop member 289 is provided with a threaded opening which is engaged by an adjusting screw 297 having a shaft 299 at its lower end rotatable in an opening in the housing member 173. The shaft 299 has fixed thereto a manual knob 301 for rotating the screw 297 and thereby moves the adjustable stop member up or down depending on the direction of rotation of the screw. Movement of the adjustable stop varies the opening of the valve 209—211 and thereby varies the amount of long time delay.

The long-time-delay adjusting device is provided with a pointer 303 similar to the pointer 279 (Fig. 5) for the short-time-delay adjustment. The pointer 303 is U-shaped and straddles the adjusting screw 297 and the S-shaped stop member 289. The two legs (only one being shown) 30 of the pointer engage in notches 305 in opposite sides of the stop member and pivotally engage a shoulder 307 on the housing member 171. The pointer 303 is biased downwardly by a spring 309 and has a reduced portion 311 projecting through a slot 313 in the scale plate 245 to indicate the setting of the long-time-delay device.

An adjustment is provided for varying the long-time-delay pick-up point, that is, the minimum overload current required to actuate the main armature 153. This adjustment comprises a member 315 (Figs. 3 and 4) having one end bifurcated and the legs 317 thereof pivotally supported in openings 319 (Fig. 3) of the housing member 171. The right-hand end of the member 315 is U-shaped and has opposed inwardly extending projections 321 engaging an annular groove 323 in the lower portion 157 of the armature 153. The projections 321 are biased by means of a spring 325 against the lower wall of the groove 323, thus biasing the armature against attraction. The spring 325 has one end hooked into an opening in the member 315 and the other end attached to an adjustable member 327 threadedly engaging an adjusting screw 329. The adjusting screw 329 is secured to a shaft 331 rotatably supported in the housing member 173 and having a manual knob 333 secured thereto bearing against the bottom of the housing member 173. The adjustable member 327 is provided with a reduced portion 335 extending through a slot 337 in the scale plate 245 to indicate the setting of the long-time-delay pick-up. Rotation of the screw 329 will move the member 327 up or down depending on the direction of rotation and accordingly vary the tension of the spring 325 and, hence, the pick-up point of the long-time-delay means. The scale plate 245 bears indicia adjacent the several pointers, as shown in Fig. 7, to indicate the settings of the several adjustments 70 of the trip device.

The trip device functions with time delays of different duration in two distinct ranges of overcurrents below a predetermined magnitude and 75 instantaneously in response to overcurrents

above the predetermined magnitude, or in response to short circuit currents. The ranges of overcurrents may be arbitrarily defined as, for example, a low range up to 500% or 600% of normal rated current, an intermediate range between 500% or 600% and 1000% of normal rated current, and instantaneous 1000% or more of normal rated current.

Assuming an overcurrent within the low range of overcurrents, the trip device, with particular reference to Fig. 8, will operate as follows: Upon the occurrence of an overcurrent in the low range of overcurrents, the electromagnet becomes energized and attracts the armature 153 upwardly. The armature acts through the spring 163 and the collar 159 to produce an upward thrust on the trip rod 161, the movement of the trip rod being retarded by the partial vacuum below the diaphragm or movable abutment 167. The initial upward movement of the trip rod causes the valve facing 189 to engage the valve seat 192 on the clamp member 179 to thereby completely seal off the spaces above and below the diaphragm 167.

The trip rod 161 moves slowly upwardly in tripping direction as air is drawn into the space below the diaphragm through the valve 209-211 until the upper end of the trip rod engages the headed screw 99 (Fig. 1) and actuates the latch mechanism to effect tripping of the breaker in the previously described manner. The time delay provided by the long-time-delay setting of the valve 209-211 is in the order of seconds and may be varied by adjusting the valve 209-211 as previously set forth.

As soon as the breaker contacts are opened, the tripping magnet 113 is deenergized and the armature 153 and the trip rod 161 are restored by the spring 325 and the force of gravity to their Fig. 3 positions. Immediately upon deenergization of the tripping magnet 113, the armature 153 drops into engagement with the upper face of the clamp member 179. The lower end of the tubular lower portion 157 of the armature member 153 also engages the sleeve 185 and opens the valve 189-192 permitting high-speed equalization of air pressure above and below the diaphragm 167 through the opening 190 in the clamp member 179 and through openings 339 in the lower end of the armature member 157 to thereby effect high-speed return of the parts to their normal lower positions as shown in Fig. 3.

Upon the occurrence of an overcurrent in the intermediate range of overcurrents, the electromagnet 113 is energized sufficiently to attract the short-time-delay armature 221 (Figs. 4 and 5) upwardly against the adjustable stop 239 opening the valve 209-211 (Fig. 6) an amount determined by the adjustment of the stop 239. This admits air to the space below the diaphragm 167 at a higher rate and provides a relatively short time delay in the order of alternating-current cycles in the operation of the trip rod.

Energization of the tripping magnet 113 in response to overcurrents in the intermediate range is not sufficient to attract the armature 229; however, upon the occurrence of an overcurrent of 1000% or more of rated current or a short circuit current, both the short-time-delay armature 221 and the instantaneous armature 229 are attracted upwardly and move the valve member 207 to its full extent, thus fully opening the valve 209-211 thereby admitting air to the space below the diaphragm 167 at a rate to permit sub-

stantially instantaneous tripping movement of the trip rod 161.

On short-time-delay and instantaneous tripping operations, the spring 163 limits the force applied by the moving armature 153 to the time-delay device. On such operations the armature 153 is attracted immediately against the fixed core member 129 comprising the spring 163 which thus supplies the force necessary to actuate the trip rod 161. Thus, the pull exerted on the time-delay device is limited to the maximum force exerted by the spring 163 when it is compressed. This prevents damage to the time-delay device and provides a uniform pull on the time-delay device.

The circuit breaker is well adapted for the protection of distribution systems. Such systems are usually protected by a series of breakers including generator breakers, bus tie-in breakers, feeder breakers and load breakers. The circuit breakers of such systems are usually adjusted for selective tripping; that is, if a fault should occur at any point in the system, the breaker nearest the fault and on the generator side of the fault should open to clear the fault condition.

The time-current requirement of the tripping device varies with the position of the breaker in the selective system for which reason a trip device providing a wide range of adjustment is essential. As shown in Fig. 9, the trip device is capable of a wide range of adjustments. There are five separate adjusting devices all located outside the device for ease of accessibility. By way of example of the ranges of adjustments, the following have been arbitrarily selected as illustrative of ranges of adjustments:

1. Range of long-time-delay pick-up, from 89% to 160% of coil rating.
2. Range of long time delay, from 23 to 86 seconds.
3. Range of short-time-delay pick-up from 500% to 1000% of coil rating.
4. Range of short time delay, from 4 to 30 alternating-current cycles.
5. Range of instantaneous pick-up, from 1000% to 1500% of coil rating.

Fig. 9 graphically illustrates the ranges of the several adjustments of the trip device. Along the left-hand edge of Fig. 3 is indicated the time in seconds. The percentage of coil rating is shown along the bottom, and the time in alternating-current cycles based on 60-cycle frequency is shown along the right-hand edge of Fig. 9. Curve A represents the minimum settings and curve B, the maximum settings. By adjusting the knob 333 (Figs. 3, 7 and 8) the long-time-delay pick-up may be adjusted to pick up at any point in the band of adjustments defined by curves A-B as indicated at C, that is, for example, between 80% and 160% of coil rating. Adjusting the knob 301 (Figs. 6, 7 and 8) which controls the initial opening of the valve 209-211 varies the amount of long time delay between 23 and 86 seconds as indicated at D in Fig. 9. As indicated at E (Fig. 9) the short-time-delay pick-up may be set to pick up between 500% and 1000% of coil rating. This is effected by adjusting the knob 255 (Figs. 7 and 8). The amount of short time delay may be varied between 4 and 30 cycles, as indicated at F, by adjusting the knob 277 (Figs. 5, 7 and 8). Finally the instantaneous pick-up point may be varied between 1000% and 1500% of coil rating, as indicated at G in Fig. 8 by adjusting the knob 247 (Figs. 7

and 3) which controls the tension of the biasing spring 235 for the instantaneous armature 229.

Each of these adjustments may be easily made by merely turning the adjusting knob associated with the particular adjusting device previously described. The adjustments are independent of each other and, as shown in Fig. 7, all of the adjusting knobs are conveniently located.

The complete adjustability of the trip device eliminates the necessity of increasing band width 10 of adjustments to compensate for manufacturing variations and different coil ratings. The variations of tripping time due to temperature changes is negligible. This is made possible by the use of air as the delaying medium. The 15 tripping time depends on the velocity of air flow through the valve orifice and is not affected by changes in air density.

Having described the invention in accordance with the patent statutes, it is to be understood that various changes and modifications may be made in the structural details and combination of elements disclosed without departing from some of the essential features of the invention.

We claim as our invention:

1. In an electromagnetic trip device including a trip rod movable to effect a tripping operation, said trip device comprising an energizing winding, an armature operable upon energization of said winding to move said trip rod, a time-delay element for retarding tripping movement of said trip rod having a chamber, a normally open valve for admitting fluid to said chamber at a predetermined rate to effect a relatively long time delay in the tripping movement of said trip rod, and a second armature operable by energization of said winding in response to certain abnormal circuit conditions to actuate said valve and increase the rate of admission of fluid to said chamber to effect a relatively short time delay in the tripping movement of said trip rod.

2. In a circuit breaker having relatively movable contact means and operating means therefor, the combination of a trip member operable to effect a tripping operation, an electromagnetic trip device comprising an energizing winding, an armature operable upon energization of said winding in response to overload currents to operate said trip member, a time-delay element for retarding tripping operation of said trip member having a chamber, a valve having an initial open position for admitting fluid to said chamber at a predetermined rate to effect a relatively long time delay in the tripping operation of said trip member, a valve-operating armature operable upon energization of said winding in response to predetermined abnormal circuit conditions to actuate said valve and increase the rate of admission of fluid to said chamber to effect a relatively short time delay in the operation of said trip member, and adjusting means for adjusting the initial open position of said valve to vary the amount of time delay provided by said initial open position of said valve.

3. In a circuit breaker having relatively movable contact means and operating means therefor, the combination of a trip member operable to effect a tripping operation, an electromagnetic trip device comprising an energizing winding, an armature operable upon energization of said winding in response to overload currents to operate said trip member, a time-delay element for retarding tripping operation of said trip member having a chamber, a valve having an initial open position for admitting fluid to said chamber at a predetermined rate to effect a relatively long time delay in the tripping operation of said trip member, a valve-operating armature operable upon energization of said winding in response to predetermined abnormal circuit conditions to actuate said valve and increase the rate of admission of fluid to said chamber to effect a relatively short time delay in the operation of said trip member, and adjusting means for adjusting the initial open position of said valve to vary the amount of time delay provided by said initial open position of said valve.

ber at a predetermined rate to effect a relatively long time delay in the tripping operation of said trip member, a valve-operating armature operable upon energization of said winding in response to predetermined abnormal circuit conditions to actuate said valve and increase the rate of admission of fluid to said chamber to effect a relatively short time delay in the operation of said trip member, and adjusting means for adjusting the initial open position of said valve to vary the amount of time delay provided by said initial open position of said valve, an adjustable stop for limiting the opening movement of said valve-operating armature, and adjusting means for varying the setting of said adjustable stop to vary the extent of opening of said valve and the amount of said short time delay.

4. In a circuit breaker having relatively movable contacts and operating means therefor, the combination of a trip rod, an electromagnetic trip device comprising an energizing winding, an armature operable upon energization of said winding in response to overload currents to operate said trip rod, a time-delay element for retarding tripping operation of said trip rod including a chamber, a valve having an initial open position for admitting fluid to said chamber at a predetermined rate to effect a relatively long time delay in the operation of said trip rod, a first valve-operating armature operable upon energization of said winding in response to overload currents below a predetermined value to actuate said valve to predetermined distance in opening direction to increase the rate of admission of fluid to said chamber to thereby effect a relatively short time delay in the operation of said trip rod, and a second valve-operating armature operable upon energization of said winding in response to overload currents above said predetermined value to actuate said valve to the full open position and permit instantaneous operation of said trip rod.

5. In an electromagnetic trip device comprising a trip member, an energizing winding, an armature operable upon energization of said winding to actuate said trip member, a time-delay element comprising a movable abutment for retarding tripping movement of said trip member, means defining a chamber, a valve for admitting fluid to said chamber, a first valve-operating armature operable upon energization of said winding in response to overload currents below a predetermined value to open said valve a predetermined distance to admit fluid to said chamber at a predetermined rate to retard tripping movement of said trip member, and a second valve-operating armature operable upon energization of said winding in response to overload currents above said predetermined value to actuate said valve to the full open position to permit instantaneous operation of said trip member.

6. In an electromagnetic trip device comprising a trip member, an energizing winding, an armature operable upon energization of said winding to actuate said trip member, a time-delay element comprising a movable abutment for retarding tripping movement of said trip member, means defining a chamber, a valve for admitting fluid to said chamber, a first valve-operating armature operable upon energization of said winding in response to overload currents below a predetermined value to open said valve a predetermined distance to admit fluid to said chamber at a predetermined rate to retard tripping movement of said trip member, and a second valve-operating armature operable upon energization of said winding in response to overload currents above said predetermined value to actuate said valve to the full open position to permit instantaneous operation of said trip member.

chamber at a predetermined rate to retard tripping movement of said trip member, and a second valve-operating armature operable upon energization of said winding in response to overload currents above said predetermined value to actuate said valve to the full open position to permit instantaneous operation of said trip member, and adjustable means for varying the amount of opening of said valve by said first valve-operating armature to vary the amount of time delay.

7. In an electromagnetic trip device comprising a trip member, an energizing winding, an armature operable upon energization of said winding in response to overload currents to actuate said trip member, a time-delay device comprising a fluid dashpot for retarding tripping movement of said trip member, a single valve controlling a passage for admitting fluid to said dashpot, a pair of valve-operating armatures for actuating said valve in opening direction to admit fluid to said dashpot to permit tripping movement of said trip member, means limiting the movement of one of said armatures to thereby limit the amount of opening of said valve when said valve is operated by said one armature to provide a time delay in the tripping movement of said trip member.

8. In an electromagnetic trip device comprising a trip member, an energizing winding, an armature operable upon energization of said winding in response to overload currents to actuate said trip member, a time-delay device comprising a fluid dashpot for retarding tripping movement of said trip member, a single valve controlling a passage for admitting fluid to said dashpot, a pair of valve-operating armatures for actuating said valve in opening direction to admit fluid to said dashpot to permit tripping movement of said trip member, means limiting the movement of one of said armatures to thereby limit the amount of opening of said valve when said valve is operated by said one armature to provide a time delay in the tripping movement of said trip member, and adjusting means for varying the amount of opening of said valve by said one armature to thereby vary the amount of time delay.

9. In an electromagnetic trip device comprising a trip member, an energizing winding, an armature operable upon energization of said winding in response to overload currents to operate said trip member, a time-delay device comprising a fluid dashpot for retarding tripping movement of said trip member, a single valve controlling a passage for admitting fluid to said dashpot, said valve having a normal partially open position for admitting fluid to said dashpot at a predetermined rate to effect a relatively long time delay in the tripping operation of said trip member, a first armature operable when said winding is energized in response to overload currents below a predetermined value to actuate said valve to an intermediate open position to increase the flow of fluid to said dashpot and thereby effect a relatively short time delay in the operation of said trip member, and a second armature operable when said winding is energized in response to overload currents above said predetermined value to actuate said valve to a full open position to permit instantaneous operation of said trip member.

10. In an electromagnetic trip device comprising a trip member, an energizing winding, an armature operable upon energization of said winding in response to overload currents to op-

erate said trip member, a time-delay device comprising a fluid dashpot for retarding tripping movement of said trip member, a single valve controlling a passage for admitting fluid to said dashpot, said valve having a normal partially open position for admitting fluid to said dashpot at a predetermined rate to effect a relatively long time delay in the tripping operation of said trip member, a first armature operable when said winding is energized in response to overload currents below a predetermined value to actuate said valve to an intermediate open position to increase the flow of fluid to said dashpot and thereby effect a relatively short time delay in the operation of said trip member, and a second armature operable when said winding is energized in response to overload currents above said predetermined value to actuate said valve to a full open position to permit instantaneous operation of said trip member, and separate adjusting means for selectively determining said partially open position of said valve and said intermediate open position of said valve to vary the amount of long time delay and short time delay.

11. In a circuit breaker having relatively movable contact means and operating means therefor, the combination of trip means, electroresponsive means for operating said trip means, time-delay means comprising a fluid dashpot for retarding tripping operation of said trip means, a valve for admitting fluid to said dashpot, means restraining said valve in a partially open position to admit fluid to said dashpot at a predetermined rate to effect a long time delay in the order of seconds in the operation of said trip means, a first armature operable when said electroresponsive means is energized in response to overload currents below a predetermined value to actuate said valve and cause said valve to increase the rate of admission of fluid to said dashpot to effect a short time delay in the order of alternating-current cycles in the operation of said trip means, and a second armature operable when said electroresponsive means is energized in response to overload currents above said predetermined value to actuate said valve to full open position to admit fluid to said dashpot at a rate to permit instantaneous operation of said trip means.

12. In a circuit breaker having relatively movable contact means and operating means therefor, the combination of trip means, electroresponsive means for operating said trip means, time-delay means comprising a fluid dashpot for retarding tripping operation of said trip means, a valve having an initial open position and operable to intermediate and full open position to admit fluid to said dashpot, separate manual means for adjustably determining the extent of opening of said valve in said initial and intermediate position, said valve in said initial open position admitting fluid to said dashpot at a predetermined rate to effect a relatively long time delay in the operation of said trip means, a first armature operable when said electroresponsive means is energized in response to overload currents below a predetermined value to operate said valve to said intermediate open position to increase the rate of admission of fluid to said dashpot to thereby effect a relatively short time delay in the operation of said trip means, a second armature operable when said electroresponsive means is energized in response to overload currents above said predetermined value to operate said valve to the full open position to admit

fluid to said dashpot at a rate to permit instantaneous operation of said trip means, and separate adjusting means for said first and second armatures for selectively determining the minimum overload currents required to actuate said armatures.

13. In a circuit breaker having relatively movable contact means and operating means therefor, the combination of trip means, electroresponsive means for operating said trip means, time-delay means comprising a fluid dashpot for retarding tripping operation of said trip means, a valve operable to an intermediate position and to a full open position to admit fluid to said dashpot, a first armature operable when said electroresponsive means is energized in response to overload currents below a predetermined value to operate said valve to said intermediate position to admit fluid to said dashpot at a rate to effect a time delay in the operation of said trip means, and a second armature operable when said electroresponsive means is energized in response to overload currents above said predetermined value to operate said valve to full open position to admit fluid to said dashpot at a rate to permit instantaneous operation of said trip means.

14. In a circuit breaker having relatively movable contact means and operating means therefor, the combination of trip means, electroresponsive means for operating said trip means, time-delay means comprising a fluid dashpot for retarding tripping operation of said trip means, a valve operable to an intermediate position and to a full open position to admit fluid to said dashpot, a first armature operable when said electroresponsive means is energized in response to overload currents below a predetermined value to operate said valve to said intermediate position to admit fluid to said dashpot at a rate to effect a time delay in the operation of said trip means, and a second armature operable when said electroresponsive means is energized in response to overload currents above said predetermined value to operate said valve to full open position to admit fluid to said dashpot at a rate to permit instantaneous operation of said trip means, separate biasing means biasing said armatures against operation, and separate adjusting means for varying the bias of said biasing means to vary the minimum overload currents required to operate said armatures.

15. In a circuit breaker having relatively movable contact means and operating means therefor, the combination of trip means, electroresponsive means for operating said trip means, time-delay means comprising a fluid dashpot for retarding tripping operation of said trip means, a valve operable to an intermediate position and to a full open position to admit fluid to said dashpot, a pivot armature operable when said electroresponsive means is energized in response to overload currents below a predetermined value to operate said valve to said intermediate position to admit fluid to said dashpot at a rate to effect a time delay in the operation of said trip means, adjustable means for selectively determining the extent of opening of said valve by said first armature to vary the amount of time delay, and a second armature operable when said electroresponsive means is energized in response to overload currents above said predetermined value to operate said valve to full open position to admit fluid to said dashpot at a rate to permit instantaneous operation of said trip means.

16. In an electromagnetic trip device comprising a trip rod, a main armature movable to actuate said trip rod, time-delay means for retarding tripping movement of said trip rod comprising a fluid dashpot connected to said trip rod, a single valve openable to admit fluid to said dashpot at different rates, and a plurality of valve-operating armatures operable upon energization of said electromagnetic means in response to overload currents of different magnitudes to open said valve different extents.

17. In an electromagnetic trip device comprising a trip rod, a main armature movable to actuate said trip rod, time-delay means for retarding tripping movement of said trip rod comprising a fluid dashpot connected to said trip rod, a single valve openable to admit fluid to said dashpot at different rates, and a plurality of valve-operating armatures operable upon energization of said electromagnetic means in response to overload currents of different magnitudes to open said valve different extents, and adjustable means for varying the extent of opening movement of one of said armatures.

18. In an electromagnetic trip device comprising a trip rod, a main armature movable to actuate said trip rod, time-delay means for retarding tripping movement of said trip rod comprising a fluid dashpot connected to said trip rod, a single valve openable to admit fluid to said dashpot at different rates, and a plurality of valve-operating armatures operable upon energization of said electromagnetic means in response to overload currents of different magnitudes to open said valve different extents, separate biasing means for said main armature and each of said valve operating armatures, and a separate adjusting device for adjusting each of said biasing means to vary the minimum overload current required to operate said main armature and each of said valve-operating armatures.

19. In a circuit breaker having relatively movable contact means and operating means therefor, the combination of a trip member, electromagnetic means for operating said trip member, a time-delay device for retarding operation of said trip member, a single control element for said time-delay device, said control element having a first position in which said control element controls said time-delay device to effect a relatively long time delay in the operation of said trip member, adjusting means for adjusting the first position of said control element to vary the amount of time delay provided by said time-delay device in the first position of said control element, biasing means for said electromagnetic means, adjusting means for adjusting said biasing means to vary the minimum overload current required to operate said trip member, a first electroresponsive means responsive to overload currents below a predetermined value to move said control element to a second position to effect a relatively short time delay in the operation of said trip member, adjusting means for adjusting said second position of said control element to vary the amount of time delay provided by said time-delay device when said control element is in said second position, biasing means biasing said first electroresponsive means against operation, adjusting means for adjusting said biasing means to vary the minimum overload current required to operate said first electroresponsive means to move said control element to said second position, a second electroresponsive means responsive

to overload currents above said predetermined value to move said control element to a third position to effect instantaneous operation of said trip member, biasing means biasing said second electroresponsive means against operation, and adjusting means for adjusting said biasing means to vary the minimum overload current required to operate said second electroresponsive means and move said control element to said third position.
